US00D843266S

(12) **United States Design Patent** (10) **Patent No.:** **US D843,266 S**
(45) **Date of Patent:** **** Mar. 19, 2019**

(54) **AERIAL VEHICLE**

(71) Applicant: **SZ DJI Technology Co., LTD,**
Shenzhen (CN)

(72) Inventors: **Shaojie Chen**, Shenzhen (CN); **Zhen Wang**, Shenzhen (CN); **Yun Zhao**, Shenzhen (CN)

(73) Assignee: **SZ DJI Technology Co., Ltd.**,
Shenzhen (CN)

(**) Term: **15 Years**

(21) Appl. No.: **29/552,818**

(22) Filed: **Jan. 26, 2016**

(51) LOC (11) Cl. **12-07**

(52) U.S. Cl.

USPC **D12/16.1**

(58) **Field of Classification Search**

Goldstein & Fox P.L.L.C.

(57) **CLAIM**

The ornamental design for an aerial vehicle, as shown and described.

DESCRIPTION

FIG. 1 is a top front perspective view of an aerial vehicle showing the claimed design;

FIG. 2 is a top front perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The dashed broken lines in the figures show portions of the aerial vehicle that form no part of the claimed design.

The shade lines in the figures show contour and not surface ornamentation.

The dot-dash broken lines in the figures show boundaries that form no part of the claimed design and the areas within the dot-dash broken lines show portions of the aerial vehicle that form no part of the claimed design.

1 Claim, 8 Drawing Sheets
